(57) **CLAIM**

The ornamental design for an asymmetrical contactless data card with off-center aperture, as shown and described.

DESCRIPTION

FIG. 1 is a perspective view of an asymmetrical contactless data card with off-center aperture according to a first embodiment of my new design;

FIG. 2 is a front elevation view thereof;

FIG. 3 is left side view elevation view thereof;

FIG. 4 is a right side elevation view thereof;

FIG. 5 is a rear elevational view thereof;

FIG. 6 is a top view thereof;

FIG. 7 is a bottom view thereof;

FIG. 8 is a perspective view of a second embodiment of my new design;

FIG. 9 is a front elevational view thereof;

FIG. 10 is a left side view elevation view thereof;

FIG. 11 is a right side elevation view thereof;

FIG. 12 is a rear elevation view thereof;

FIG. 13 is a top view thereof; and,

FIG. 14 is a bottom view thereof.
